(57) **CLAIM**

The ornamental design for a candle, as shown and described.

DESCRIPTION

FIG. 1 is a front view of a candle showing my new design, the rear, right-side and left-side view being the same;

FIG. 2 is a top plan view thereof;

FIG. 3 is a bottom plan view thereof;

FIG. 4 is a top perspective view thereof; and,

FIG. 5 is a bottom perspective view thereof.

The broken lines in the drawings are included for the purpose of illustrating environmental subject matter and form no part of the claimed design.
